UNITED STATES PATENT OFFICE.

JOHN L. TAYLOR, OF CHICAGO, ILLINOIS, ASSIGNOR TO HARRY D. YERXA, OF CHICAGO, ILLINOIS.

DESIGN FOR A CASING FOR VENDING-MACHINES.

45,697.

Specification for Design.

Patented Apr. 28, 1914.

Application filed February 28, 1914. Serial No. 821,806. Term of patent 14 years.

To all whom it may concern:

Be it known that I, JOHN L. TAYLOR, a citizen of the United States, residing at Chicago, in the county of Cook and State of Illinois, have invented a certain new, original, and ornamental Design for a Casing for Vending-Machines, of which the following is a specification, reference being had to the accompanying drawing, forming a part thereof.

The figure is a perspective view of a cas-

ing for a vending machine, showing my new design.

I claim:

The ornamental design for a casing for vending machine, as shown.

In testimony whereof I hereunto affix my signature in presence of two witnesses.

JOHN L. TAYLOR.
